(57) **CLAIM**

The ornamental design for a ground anchor, as shown and described.

DESCRIPTION

FIG. 1 is a front perspective view of a ground anchor, showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 shows the ground anchor of FIG. 1 in a state of use.

1 Claim, 8 Drawing Sheets
